UNITED STATES PATENT OFFICE.

RUDOLF LOEB, OF JENKINTOWN, PENNSYLVANIA.

OVEREDGE OR OVERLOCK SEWING-MACHINE.

1,262,070.

Specification of Letters Patent.

Patented Apr. 9, 1918.

Application filed March 25, 1915. Serial No. 16,899.

To all whom it may concern:

Be it known that I, RUDOLF LOEB, a citizen of the United States, and a resident of Jenkintown, Montgomery county, Pennsylvania, have invented certain Improvements in Overedge or Overlock Sewing-Machines, of which the following is a specification.

My invention relates to sewing machines of the overedge or overlock stitch type; and 10 the object of my invention is to provide a machine of the general character such as illustrated in the patent of Willcox and Borton, No. 472,095, with means whereby the overlock or overedge stitches produced by 15 such machine may be graduated or varied in length to effect the formation of a scalloped edge ornamentation for the fabric. In such scalloped edge ornamentation, the shorter stitches will be slightly raised or 20 stuffed due to the infolding or turning of portions of the fabric inclosed thereby.

These and other features of my invention are more fully described hereinafter, reference being had to the accompanying drawings, in which:

Figure 1, is a plan view of a machine embodying the improvements forming the subject of my invention;

Fig. 2, is a side elevation of the same;

Fig. 3, is a front elevation;

Figs. 4 and 5, are sectional views of details of my invention;

Fig. 6, is a perspective view illustrating the particular character of stitch regulating 35 means constituting the subject of my invention;

Figs. 7, 8, 9, 10, 11 and 12, are perspective views showing the manner in which the stitches of varying length are formed, and

40 Figs. 13 and 14, are sectional views of the fabric at different points of the edge of the same, showing the stitches applied thereto.

The whole purpose and function of my 45 invention is to apply stitches which vary in length, and in the particular embodiment of my invention as illustrated, these stitches gradually increase in length until the maximum length is reached, and then gradually 50 decrease in length until the minimum length is reached; the whole being carried on automatically and continuously whereby a scalloped edge is formed of what may be termed overlock or overedge stitches.

55 The operation of this machine, in general, is similar to the patent before referred to,

and the manner of manipulating the particular portions constituting my improvements is as follows:

In the operation of laying the short and 60 long stitches in the formation of the improved embroidery edging, I provide a movable wedge-shaped member 1 over which the stitches are formed, which member is moved at regular intervals with relation to the 65 point at which the stitches are laid, with the result that short stitches will be formed over the point of the member when moved in one direction; such stitches gradually lengthening to the full sized stitches formed 70 over the main body or heel of such stitch member and gradually shortening as the stitch member is moved in the opposite direction.

The tapering or pointed member 1 over 75 which the stitches are formed is reciprocated back and forth with respect to the point at which the stitches are laid, and movement of this member may be effected by a lever 2 having a cam groove 3 in which a roller 4 is 80 vertically reciprocated; such roller being actuated from a suitable part of the machine in a manner hereinafter described.

In the formation of the short and long 85 stitches, it is, of course, necessary to alter at regular intervals the amount of thread fed to the stitch-forming elements, and hence I provide special tension means for the several threads; the operation of such tension means coördinating with the movements of the stitch forming element, so that while sufficient thread will be provided for the several stitches the tension on the same will be increased for the shorter stitches. This tension may be controlled by a second 90 lever 2^a actuated by similar means and moving in consonance with the lever 2 actuating the member 1 over which the stitches are formed.

The machine to which my improvements 100 have been applied is provided with the usual needle 5 of a character substantially similar to that disclosed in the patent before referred to, which needle coöperates with a hook 6 also substantially like that shown in 105 the patent referred to, and operated in a similar manner. To the needle and hook respectively, threads 7 and 8 are led from suitable cops or spools, and when the machine is once started, stitching will be carried 110 on continuously; the fabric being sheared ahead of the stitching in the manner common

to the operation of machines of this character.

During this stitching, however, the stitch forming member 1 is reciprocated, so that 5 short and long stitches may be laid over the same and simultaneously with such movement of the stitch-forming member, tension is applied to and released from the hook thread, in order that a greater tension will 10 be imparted thereto when the shorter stitches are being laid in order that they may be drawn close against the edges of the fabric; thereby folding portions of the same, and effecting the desired scallop formation.

15 The stitch forming member 1 is carried by a lever 2; being mounted upon a pin 9 20 slidable with respect to the foot 10 of the machine. The pin 9 has secured to its rear end a clamp 9^a which lies in the lower slotted end of the lever 2 and has a portion bearing against said lever. This clamp carries a roller 9^b which is adapted to rise and fall in grooves 9^c formed in the lever 2, so that while said lever has a rocking movement, a 25 horizontal reciprocative movement will be imparted thereby to the stitch forming member 1. This lever 2 is pivotally hung on a spindle 11 whereby it may rock or swing; such spindle being supported by a suitable 30 standard 12, and oppositely disposed with respect to this lever 2, is a second lever 2^a of the bell crank type, having an arm 13 operatively connected to a spring-pressed post 14 which controls tension disks 15 for 35 the hook thread 8.

The inner faces of the respective levers 2 and 2^a are provided with cam grooves 3 and 3^a which may be formed by ribs 16 set at an angle with respect to said levers, and 40 rollers or pins 4 and 4^a are adapted to these grooves, which rollers or pins are carried by a vertically sliding support 17, so that movement of the latter will rock the levers 2 and 2^a on their pivotal connection with 45 the spindle 11 and effect proper movement of the member 1 over which the stitches are formed on the one hand, and increase the tension on the thread 8 on the other hand. In addition, I provide an arm 18 50 with tension plates 19 through which the thread is guided.

The ribs 16 are formed on plates 20 and 20^a pivotally secured to the levers 2 and 2^a by screws 21 and 21^a, and these plates are 55 adjustable on said levers; having pins 22 and 22^a adapted to arcuate slots 23 and 23^a in said levers 2 and 2^a. The position of the plates 20 and 20^a may be regulated by means of set screws 2^b carried by the levers 2 and 60 2^a and bearing against the pins 22 and 22^a; the position of said cam grooves determining the extent of movement of the levers 2 and 2^a. This adjustment is relatively delicate.

65 The vertically moving member 17 is

guided in a suitable block 24 carried on the spindle 11 and motion is imparted in the following manner:

On the main driving shaft of the machine I provide a worm 25 meshing with a 70 worm wheel 26 on a shaft 27 carrying an eccentric 28 driving a pitman 29; the opposite end of which pitman is connected at 30 to a horizontal sliding member 31 suitably guided by slotting the same at 32 and 75 permitting it to work over pins 33. This sliding member has an upwardly projecting portion 34 with a cam slot 35 therein, and adapted to said cam slot is a roller 36 carried by the lower forked end 37 of a stem 80 38 which carries at its upper end an arm 39 connected to and operating the vertically sliding member 17. By preference the forked end 37 is separate from the stem 38 and connected thereto by a screw 40 in 85 order that the parts of the mechanism may be taken down without the necessity of dismantling the upper portion of the structure.

The movement of the stitch forming member 1 may be regulated to effect changes in 90 the length of the scallops by changing the relation of the worm and worm wheel; a greater number of teeth in the worm wheel increasing the length of the scallop and vice versa. Variation in the character of the 95 scallop may be effected by altering the shape of the cam slot 35 which has a definite throw with reference to the size of the eccentric. A different sized eccentric would be combined with a pitman having a greater throw 100 and the cam slot 35 would be lengthened; resulting in the lengthening of the scallop. The same result might be attained by increasing the angle of the cam slot and reducing the speed of the pitman by effecting 105 necessary changes in the gearing.

Variations in the character of the slot may be made to alter the character of the scallop. If portions of the cam slot were horizontally 110 disposed, the stitch forming member would be caused to dwell in one position until a number of stitches were formed and this dwell might be arranged to occur at the high portion of this member or at the point of the same.

The position of the plates 20 and 20^a having the ribs 16 forming the cam grooves 3 and 3^a is also a factor in determining the length of the scallops.

The movement of the stitch forming 120 mechanism is readily regulable therefor and while it takes place during the operation of the stitch laying mechanism, its timing and actual movement has no connection with the speed of such stitch laying mechanism. 125 The gearing, of course, is driven from the main driving shaft of the machine.

I claim:

1. In an overedge or overlock sewing machine, the combination with stitch forming 130

mechanism, of a reciprocating member over which the stitches are formed, said member being tapered and serving to effect the formation of stitches of varying length at 5 different points around the same, tension means for the thread passing over said reciprocating member, and means for effecting movement of said reciprocating member coördinately with the action of said tension means; the tension on the thread being inversely proportional to the size of the stitch formed over the tapering member.

2. In an overedge or overlock sewing machine, the combination with stitch forming 15 mechanism including a plurality of elements for laying a plurality of threads to form interconnected stitches, of a reciprocating member over which the stitches are formed, said member being shaped to effect 20 the formation of stitches of varying length at different points throughout its length, tension means for the thread passing over said reciprocating means, and means for moving said reciprocating member coördinately with the action of said tension means; the tension on the thread being inversely proportional to the size of the stitch formed over the tapering member.

3. In an overedge or overlock sewing machine, the combination with stitch forming 30 mechanism, of a reciprocating member over which the stitches are formed, tension means for the thread passing over said reciprocating member, said member serving to effect 35 the formation of stitches of varying length, means for causing said tension device to exert greater pull upon the thread when the shorter stitches are being formed, and means for operating said reciprocating member coördinately with the actuation of said tension device.

4. In an overedge or overlock sewing machine, the combination with stitch forming 45 mechanism, of a reciprocating member over which the stitches are formed, said member being tapered, tension means for the thread passing over said reciprocating member, said member serving to effect the formation 50 of stitches of varying length in regular gradation, means for causing said tension device to exert greater pull upon the thread when the shorter stitches are being formed, and means for operating said reciprocating member coördinately with the actuation of 55 said tension device.

5. In an overedge or overlock sewing machine, the combination with stitch forming mechanism, of a reciprocating member over which the stitches are formed, tension means 60 for the thread passing over said reciprocating member, the latter serving to effect the formation of stitches of varying length, a pair of levers, one of said levers controlling the tension device and the other lever carrying the reciprocating member, a pivotal con-

nection for said levers, and means for rocking said levers on their pivotal connection.

6. In an overedge or overlock sewing machine, the combination with stitch forming mechanism, of a reciprocating member over 70 which the stitches are formed, said member being tapered, tension means for the thread passing over said reciprocating member, the latter serving to effect the formation of 75 stitches of varying length in regular gradation, a pair of levers, one of said levers controlling the tension device and the other lever carrying the reciprocating member, a pivotal connection for said levers, and means for rocking said levers on their pivotal connection.

7. In an overedge or overlock sewing machine, the combination with stitch forming mechanism, of a tapered reciprocating member over which the stitches are formed, the 85 point of formation of a stitch upon such member regulating the size of the same, a lever carrying said member and having a cam groove, vertically movable means in engagement with said cam groove for rocking 90 the lever upon its pivot and effecting movement of the reciprocating member, tension means for the thread passing over said reciprocating member, and means for actuating said tension means coördinately with 95 the movement of the tapering reciprocating member; the tension on the thread being inversely proportional to the size of the stitch formed over the tapering member.

8. In an overedge or overlock sewing machine, the combination with stitch forming mechanism, of a reciprocating member over which the stitches are formed, a lever carrying said member, camming means carried by said member, vertically movable means 100 in engagement with said camming means for rocking the lever upon its pivot and effecting movement of the reciprocating member, a second lever operated by the same means, and a tension device under the control of 110 said second lever.

9. In an overedge or overlock sewing machine, the combination with a plurality of stitch forming elements and a plurality of threads laid thereby, of a reciprocating 115 member over which the stitches are formed, a lever carrying said member, camming means carried by said member, vertically movable means in engagement with said camming means for rocking the lever upon its 120 pivot and effecting movement of the reciprocating member, a second lever operated by the same means, and a tension device under the control of said second lever.

10. In an overedge or overlock sewing machine, the combination with stitch forming mechanism, of a reciprocating member over which the stitches are formed, a lever carrying said member and having a cam groove, vertically movable means in engagement 125 130

- with said cam groove for rocking the lever upon its pivot and effecting movement of the reciprocating member, a second lever operated by said vertically movable means, 5 a tension device under the control of said second lever, a horizontally movable member for effecting vertical movement of the lever rocking member, and gearing for driving said horizontally movable member.
- 10 11. In an overedge or overlock sewing machine, the combination with a plurality of stitch forming elements for laying a plurality of threads, of a tapered reciprocating member over which the stitches are formed, 15 a lever carrying said member and having a cam groove, vertically movable means in engagement with said cam groove for rocking the lever upon its pivot and effecting movement of the reciprocating member, a second 20 lever operated by said vertically movable means, a tension device under the control of said second lever, a horizontally movable member having a cam groove, an operative connection between the same and the vertically moving lever operating member, gearing, and an eccentric and pitman connection between said gearing and the horizontally movable member.
- 25 12. In an overedge or overlock sewing machine, the combination with stitch forming mechanism, of a reciprocating member over which the stitches are formed, a lever carrying said member and having a cam groove, a stem upon which said lever is pivoted, a 30 second lever mounted upon the same axis as the first and also having a cam groove, a tension device under the control of said second lever, vertically movable means in engagement with said cam grooves for rocking the 35 levers upon their pivots and effecting movement of the reciprocating member and the tension device, and means for actuating said vertically movable means.
- 40 13. In an overedge or overlock sewing machine, the combination with stitch forming mechanism, of a reciprocating member over which the stitches are formed, a lever carrying said member and having a cam groove, a stem upon which said lever is pivoted, a 45 second lever mounted upon the same axis as the first and also having a cam groove, a tension device under the control of said 50
- second lever, vertically movable means in engagement with said cam grooves for rocking the levers upon their pivots and effecting movement of the reciprocating member, a second lever, vertically movable means in engagement with said cam grooves for rocking the levers upon their pivots and effecting movement of the reciprocating member and the tension device, and means for actuating said vertically movable means in engagement with said cam grooves for rocking the levers upon their pivots and effecting movement of the reciprocating member, and means for actuating said vertically movable means, said latter means including a horizontally movable member, a pitman connected thereto, an eccentric, gearing for driving said eccentric and pitman, and a cam groove formed in the horizontally movable member for co-action with a pin carried by the vertically movable member. 55
- 60
- 65
14. In an overedge or overlock sewing machine, the combination with stitch forming mechanism, of a tapered reciprocating member over which the stitches are formed, a lever carrying said member and having a cam groove, vertically movable means in engagement with said cam groove for rocking the lever upon its pivot and effecting movement of the reciprocating member, and means for adjusting the position of such 70 cam groove.
- 75
15. In an overedge or overlock sewing machine, the combination with stitch forming mechanism, of a reciprocating member over which the stitches are formed, a lever carrying said member and having a cam groove, means adapted to said cam groove for rocking the lever, and means for adjusting the cam groove. 80
- 85
16. In an overedge or overlock sewing machine, the combination with stitch forming mechanism, of a reciprocating member over which the stitches are formed, a lever carrying said member, a plate pivotally mounted on said lever and having a cam groove, means adapted to said cam groove for rocking the lever, and means for adjusting said plate to regulate the extent of movement of the lever. 90
- 95
17. In an overlock or overedge sewing machine, the combination with stitch forming mechanism, of a reciprocating member over which the stitches are formed, a lever carrying said member, a plate pivotally mounted on said lever and having a cam groove, 100 slots in said lever, pins on the plate adapted to said slots, and set screws carried by the lever to engage said pins.

RUDOLF LOEB.
